PACKING DEVICE HAVING FASTENER
MEANS FOR FACILITATING THE FOR-
MATION OF ATTRACTIVE DISPLAY
LAYERS

George H. Herwig, Benton Harbor, Mich.

Application September 8, 1944, Serial No. 553,165

8 Claims. (Cl. 226—17)

1

This invention relates to improvements in packing devices having fastener means for facilitating the formation of attractive display layers.

The main objects of this invention are:

First, to provide a packing device which enables the rapid packing of boxes or containers for fruit or vegetables or other small objects to provide a faced package.

Second, to provide a device or apparatus of the class described in which the fruit may be packed with a facing layer by the picker with a minimum expenditure of time and effort.

Third, to provide a packing device of the class described which is very inexpensive in structure and easy to operate.

Objects relating to details and economies of the invention will appear from the description to follow. The invention is defined and pointed out in the claims.

A preferred embodiment of the invention is illustrated in the accompanying drawing, in which:

Fig. 1 is a perspective view of a packing device embodying my invention with a tubular container wall member therein, an assembled container prior to securing the members thereof together being shown.

Fig. 2 is a transverse section on line 2—2 of Fig. 1, the articles to be packed being conventionally illustrated.

Fig. 3 is a transverse section on line 3—3 of Fig. 1 with the retaining rod in retaining position.

Fig. 4 is a fragmentary section with the packing tray in inverted position and in the process of being withdrawn from the completed package, the contents of which are conventionally illustrated.

Fig. 5 is a perspective view of the filled completely assembled container with the contents conventionally illustrated.

The box or container illustrated is that of my copending application, Serial No. 533,166, filed September 8, 1944, which container is particularly well adapted for use with the packing device of this application.

In the embodiment of my invention illustrated, I provide a tray-like receptacle 1 preferably formed of sheet metal and having a wire border member 2 secured thereto by means of the outfolded border bead or roll 3. This provides a smooth or rounded edge and also stiffens the structure, permitting its being made of light sheet metal.

The structure illustrated is adapted to receive

2

four boxes or containers for packing arranged in side by side relation, two being illustrated in Fig. 1. These boxes or containers comprise tubular members 4 rectangular in cross section and a bottom member 5 having auxiliary side walls 6, the bottom being disposed across the end of the tubular member with the side walls 6 lapped upon the outer sides thereof.

The side walls 6 are provided with bendable fasteners 7, those illustrated being in the form of wire loops which are bent over the upper edges of opposed side walls as shown at 8 to secure the parts in assembled relation, the material packed being indicated conventionally at 9 in Figs. 2, 4 and 5.

It is well recognized that the attractiveness and salability of fruit and certain vegetables—mushrooms for example, is greatly influenced by proper facing of the package—that is, the arranging of good specimens of the article packed in a substantially uniform relation as is shown in the drawing. My packing tray is adapted to facilitate such packing. The tray 1 is provided with corner legs 10 adapted to support it in elevated position. In packing, the tubular members 4 are arranged within the tray, the bottom of the tray constituting a facing surface on which the articles packed may be arranged as is illustrated in Fig. 2. After the facing is arranged, the remaining contents of the container are filled in more or less promiscuously as is common practice. With the container walls filled as is indicated in Fig. 2, the bottom 5 is placed across the container with the auxiliary side wall members 6 between the sides of the tray and the opposed sides of the container. The tray is provided with openings 11 adapted to receive the fasteners 7 when the combined bottom member and auxiliary side member is placed over the filled container. The fasteners may be bent inwardly to the secured position with the tray in upright position as shown in Fig. 3 but, as a matter of substantial convenience and to enable the operator to see the work clearly, I provide means for holding the filled containers in the tray while the tray is inverted so that the operator can clearly see and more conveniently secure the fasteners 7. A simple means for accomplishing this is to provide the end walls of the tray with eyes 12 with which the rod 13 may be engaged, the rod when inserted extending across the bottoms 5 as shown in Fig. 3. This enables the inverting of the packing tray which, as stated, facilitates the securing of the fasteners and also the inverting to discharge the packages or to permit the tray

to be lifted off from the packed containers. The notches or openings will preferably extend not only into the bottom but also into the side wall.

With my improved packing devices, fruits particularly small fruits and small vegetables may be attractively packaged with a minimum of labor and this can be effectively done in the field. The trays may be used as "picking lugs". The structure illustrated is designed to receive four containers but it will be understood that it may be larger if desired. A further advantage is that no tools or other equipment are necessary for the effective packing of the faced containers.

I have illustrated and described my invention in an embodiment which I consider highly practical. I have not attempted to illustrate or describe certain modifications and adaptations as it is believed that this disclosure will enable those skilled in the art to embody or adapt my invention as may be desired.

Having thus described my invention, what I claim as new and desire to secure by Letters Patent, is:

1. In a packing apparatus, the combination of an invertible tray of rectangular section and provided with supporting legs and adapted when in upright position to receive a plurality of tubular container members rectangular in cross section and support the same in filling position with the bottom of the tray constituting a facing surface, the width of the tray being such that the side walls of the tubular container members are spaced therefrom to receive auxiliary side walls between them, the tray having opposed slot-like openings at the lower corners thereof extending into the bottom and side walls and adapted to receive projecting fasteners carried by the auxiliary side walls of a combined container bottom and side wall member and to permit the folding of such fasteners over the edges of the side walls of the tubular container member while the container members are assembled within the tray, upwardly projecting eyes on the end walls of the tray, and a container retaining rod removably engageable with said eyes and when engaged extending across the bottoms of the assembled containers facilitating the inverting of the tray with the filled containers therein and permitting the bending of the fasteners with the tray in inverted position.

2. In a packing apparatus, the combination of a tray of rectangular section and provided with supporting legs and adapted when in upright position to receive a plurality of tubular container members rectangular in cross section and support the same in filling position with the bottom of the tray constituting a facing surface, the width of the tray being such that the side walls of the tubular container members are spaced therefrom to receive auxiliary side walls between them, the tray having opposed slot-like openings at the lower corners thereof extending into the bottom and side walls and adapted to receive projecting fasteners carried by the auxiliary side walls of a combined container bottom and side wall member and to permit the folding of such fasteners over the edges of the side walls of the tubular container member while the container members are assembled within the tray, said tray supporting legs permitting said fasteners to project through said openings to below the bottom of the tray and facilitating engaging said fasteners through said openings to fold the fasteners around the edges of the side walls of the tubular containers.

3. In a packing apparatus, the combination of an invertible tray adapted when in upright position to receive a plurality of tubular container members rectangular in cross section in side by side relation and support the same in filling position with the bottom of the tray constituting a facing surface, the tray having openings adapted to receive projecting fasteners carried by the auxiliary side walls of a combined container bottom and side wall member and to permit the folding of such fasteners over the edges of the side walls of the tubular container member while the container members are assembled within the tray, and a container retaining rod removably engageable with said tray and when engaged extending across the bottoms of the assembled containers facilitating the inverting of the tray with the filled containers therein and permitting the engagement of the fasteners with the tray in inverted position.

4. In a packing apparatus, the combination of a tray adapted when in upright position to receive a plurality of tubular container members rectangular in cross section in side by side relation and support the same in filling position with the bottom of the tray constituting a facing surface, the tray having openings substantially spaced from each other and disposed through the bottom of the tray and adapted to receive projecting fasteners carried by a bottom element and to permit the folding of such fasteners over the edges of the side walls of the tubular container member while the container members are assembled within the tray.

5. In a packing apparatus, the combination of an invertible tray provided with supporting legs and adapted to receive a tubular container member and support the same in facing and filling position, the tray having opposed slot-like openings at the lower corners thereof extending into its bottom and side wall and adapted to receive projecting fasteners carried by a combined container bottom and side wall member and to permit the folding of such fasteners over the upper edges of the side walls of the tubular container member while the container members are assembled within the tray, and a container retaining rod removably engageable with said tray and when engaged extending across the bottom of the assembled container facilitating the inverting of the tray with the filled container therein and permitting the disengagement of the fasteners with the tray in inverted position.

6. In a packing apparatus, the combination of a tray provided with supporting legs and adapted to receive a tubular container member and support the same in facing and filling position, the tray having opposed slot-like openings at the lower corners thereof extending into its bottom and side wall and adapted to receive projecting fasteners carried by a combined container bottom and side wall member and to permit the folding of such fasteners over the upper edges of the side walls of the tubular container member while the container members are assembled within the tray, said tray supporting legs permitting said fasteners to project below the bottom of the tray and facilitating engaging said fasteners through said openings to fold the fasteners around the edges of the side walls of the tubular member.

7. In a packing apparatus, the combination of an invertible tray adapted to receive a tubular container member and support the same in facing and filling position, the tray having openings

adapted to receive fasteners carried by a bottom element and to permit engagement of such fasteners with the tubular container member while the container member is assembled within the tray, and a container retaining rod removably engageable with said tray and when engaged extending across the bottom of the assembled container facilitating the inverting of the tray with the filled container therein and permitting the disengagement of the fasteners with the tray in inverted position.

8. In a packing apparatus, the combination of a tray adapted to receive a tubular container member and support the same in facing and filling position, the tray having openings substantially spaced from each other and substantially spaced from the top of the tray adapted to re-

ceive fasteners carried by a bottom element and to permit engagement of such fasteners with the tubular container member while the container member and bottom element are assembled within the tray.
